PROCESS AND APPARATUS FOR PRODUCTION OF ARTIFICIAL THREAD

Paul E. Harrison, Dover, N. H., assignor to Du Pont Rayon Company, New York, N. Y., a corporation of Delaware

Application October 6, 1934, Serial No. 747,201

9 Claims. (Cl. 18—8)

This invention relates to humidification, and more particularly it relates to a method for humidifying spinning bucket compartments and apparatus for carrying out such method. The invention is concerned primarily with the prevention of crystal formation on spinning buckets and in bucket compartments used in connection with the manufacture of artificial thread.

The invention will be described in connection with the manufacture of viscose rayon, it being understood that it is not limited thereto but may be used in the manufacture of any artificial thread in the spinning of which it is desired to maintain a relatively high humidity in the bucket compartment.

During one step in the manufacture of viscose rayon by the bucket spinning process, the newly formed thread, still wet with coagulating liquor, is wound into the form of an annular cake in the centrifugal bucket. Due to the speed of the spinning bucket, a certain amount of excess liquid is thrown by the bucket onto the walls of the compartment in which the bucket is located. At low bucket speeds, no problem is caused by this discharge, but with high bucket speed, particularly in the spinning of fine filaments, enough liquid is evaporated to deposit salt crystals on the walls of the compartment, on the bucket and on the bottom of the compartment cover. These crystals on the bucket very materially increase the power load necessary to drive the bucket, and furthermore the crystals from the bottom of the compartment cover often drop into the bucket and materially damage the filaments or yarn therein.

It has been proposed to minimize crystal formation in spinning bucket compartments by squirting a stream of water or steam against the sides of the bucket. This proposed method has been found to eliminate crystal growth on the outside of the bucket and on the compartment walls but it requires the passing of fluid at relatively high pressure within the bucket compartment with the consequent danger of contacting the yarn with water. If the water contacts the yarn in the bucket, it deleteriously affects its properties. Furthermore, the passing of steam or water into the bucket compartment will very materially dilute the coagulating fluid dripping from the yarn and prevent or make uneconomical the recovery thereof.

It is an object of this invention to prevent crystallization of coagulating bath liquor in a spinning bucket compartment.

It is a further object of this invention to in-

crease the relative humidity in a spinning bucket compartment.

A still further object of this invention is to produce high quality, artificial yarn in high speed spinning buckets.

Other objects of the invention will appear hereinafter.

The objects of this invention are accomplished in general by lowering the temperature within the spinning bucket compartment and thus increasing the relative humidity to a degree which will prevent formation of crystals. This is preferably accomplished by providing a jacket or coil adjacent the external surface of the spinning compartment and circulating a refrigerating fluid or water at a comparatively low temperature therethrough.

The details and advantages of the invention will become more apparent by reference to the following detailed description taken in connection with the accompanying illustrations, in which:

Fig. 1 is a vertical sectional view of a bucket compartment showing a bucket positioned therein.

Fig. 2 is a plan view, partly in section, taken on line 2—2 of Fig. 1.

Fig. 3 is a vertical sectional view of a modified form of bucket compartment.

Fig. 4 is a plan view, partly in section, taken on line 4—4 of Fig. 3.

Referring to the accompanying illustrations, reference character 9 designates an enclosing structure connected to the frame 26 of the bucket spinning machine. This enclosing structure, in the instant case, has been shown as made of wood, but, obviously, this structure may be made of any desired material. Numeral 10 designates a ventilating duct which is adapted to connect a plurality of bucket compartments 20 so as to withdraw objectionable air and vapors from the spinning compartment. At the bottom of the ventilating duct is provided a coagulating liquid drain 11 which serves to carry the coagulating liquid or drip from the various bucket compartments to a recovery system or to the sewer, as the case may be. The duct 10 and the drain 11 extend throughout the length of the machine, which may comprise as many as 50 bucket compartments. The individual bucket compartments 20 are shown as being circular in cross-section but they may be of any desirable form or shape. Each bucket compartment is preferably provided with a cover 14 having a hole 15, which hole is positioned above the central

part of the bucket 19. The thread is admitted to the bucket 19 through a traversing funnel (not shown) and which is adapted to project through said opening 15. 16 designates a driving mechanism for imparting rotation to the bucket 19, the bucket being connected to the driving mechanism by means of a shaft 18. The various bucket compartments are connected to the main air duct 10 by means of ducts 13 so as 10 to permit a certain amount of air circulation within the bucket compartments 20. These connections between the various bucket compartments and the main air duct 10 may be provided, adjacent the outlets thereof, with any suitable 15 form of valve or damper 21 for controlling the amount of air circulation within the bucket compartment.

In the modification of the invention, as shown in Fig. 1, a plurality of coils 22 are positioned 20 around the external surface of the bucket compartment 20, the lower coil of which is connected to a header line 23, and the upper coil of which is connected to a second header line 21. Water at a predetermined temperature may be introduced 25 into the header 23 through the valve 24 (Fig. 2), from which it may flow through the various coils 22 surrounding the bucket compartments to the outlet header line 21. The amount of water passed through the header 23 30 may be controlled by means of the valve 24; furthermore, if desired, each set of coils surrounding the individual bucket compartments may also be provided with a regulating valve, such as that shown by 25. Should it be difficult to obtain 35 water at a definite predetermined, low temperature, it is obvious that any other desired refrigerating medium can be supplied to the coils 22.

In the modification shown by Figs. 3 and 4, 40 the bucket compartment 20 is provided with a jacket 31 spaced slightly therefrom so as to provide an annular chamber 31 surrounding the bucket compartment. The various chambers 31 surrounding the individual bucket compartments 45 are connected to an inlet header line 33 by means of connecting conduit 35. An outlet header line 32 is connected to the jacket 31 by means of a connecting conduit 34. The refrigerating fluid, such as water at a desired low temperature, is 50 introduced into the inlet header line 33 through the valve 36 (Fig. 4), the refrigerating fluid then rising in the chambers 31 surrounding the compartments until it reaches the overflow conduit line 34 by means of which it is carried to the 55 outlet header line 32. The rate of flow of the refrigerating fluid in this case, as in the modification shown by Figs. 1 and 2, may be controlled by means of the inlet valve 36.

The humidification system constructed in accordance with this invention is adapted to operate as follows:

The bucket 19 is rotated at high speed and thread is admitted thereto through a traversing funnel (not shown) which is positioned concentrically with the central opening 15 in the cover 14 of the bucket compartment 20. The rotation of the bucket draws air into the compartment 20 from which it is withdrawn into the ventilating duct 10. Water or other refrigerating fluid is passed through the coils 22 or the jacketed chambers 31 of the bucket compartments, the flow of which is regulated by means of the header valve 24 or 36 or by means of the individual bucket compartment valve 25. By means of 75 these valves the temperature in the bucket com-

partments may be regulated to any desired degree, and it is preferably lowered to such an extent that the relative humidity is just high enough to prevent the formation of crystals within the bucket, the bucket compartment or on 5 the bucket cover.

The temperature of the water or other refrigerating fluid and the amount thereof used in lowering the temperature of the bucket compartment will obviously vary between wide limits 10 due to variations in barometric pressure, speed of spinning, acid, salt and glucose content of the coagulating bath, denier of the filaments, and circulation of air through the spinning compartments. Under ordinary conditions, the relative 15 humidity is preferably maintained between 75% and 90% to prevent crystal formation, although in unusual cases, where the various factors causing crystal growth are all present under unfavorable circumstances, a higher relative humidity 20 may be necessary. The relative humidity may be measured in a well known manner by the use of wet and dry bulb thermometers, and the temperature and/or the rate of flow of the refrigerating medium adjusted accordingly. 25

Some advantages of this invention can be obtained by the use of non-circular compartments, but a round or volute compartment acts much more efficiently than a rectangular compartment, due to the fact that the air circulation within 30 the bucket compartment can be more efficiently regulated.

Obviously the coils, jackets or connecting ducts of the apparatus should be made of suitable corrosion-resistant material, such as for example 35 lead, nickel, aluminum, or a suitable non-metallic substance such as a phenol-aldehyde condensation product.

The supply of refrigerating medium to the coils or jackets is preferably only under sufficient pressure to insure a flow from the bottom header line to the top header line, which pressure will usually not exceed a head of 1 or 2 feet. On the other hand, should it be necessary to pass a great deal of water or other refrigerating fluid, to obtain the necessary lowering of 45 temperature, it may be passed to the coils or jackets at higher pressures, for example 2-10 lbs. per square inch, and in such case the outlet header line may be provided with a valve to aid in 50 regulating the flow of the fluid.

It is a further advantage of this invention that a compartment may be served with substantially saturated air without bringing a humidifying liquid into it and thereby cause a dilution of the coagulating liquid. Bucket spinning machines equipped with this humidification system operate without crystal formation, and as a matter of fact, this humidification system has not only prevented crystal formation but has also caused 60 the removal of the crystals already formed, which compares favorably with machines equipped with water or steam spraying means. By eliminating the formation of crystals on the buckets and compartment walls, the yarn is not 65 damaged by the crystals and a lower power load on the equipment is effected. By using low pressure water and eliminating the nozzles by which water is delivered under higher pressure, mechanical simplification is secured and difficulties 70 are eliminated. For instance, if spray jets are used with accompanying high water pressure and if a bucket should fly off the spindle or burst, the jet is usually broken and the deluge of water damages the equipment and renders the rayon 75

contacted therewith unfit for use. Other advantages of this invention are believed to be apparent.

Since it is obvious that various changes and modifications may be made in the above description and accompanying illustrations, without departing from the nature and spirit thereof, it is to be understood that the invention is not to be limited thereto except as set forth in the appended claims.

10 I claim:

1. In an apparatus for the manufacture of artificial threads, a plurality of individual compartments, centrifugal spinning buckets in said compartments, and refrigerating means for regulating the relative humidity of said compartments.

2. In an apparatus for the manufacture of artificial thread, a plurality of individual compartments, centrifugal spinning buckets in said compartments, air ducts connecting said compartments, and refrigerating means for regulating the relative humidity of said compartments.

3. In an apparatus for the manufacture of artificial threads, a plurality of individual compartments, centrifugal spinning buckets in said compartments, and refrigerating means surrounding each compartment for regulating the relative humidity therein.

25 4. In an apparatus for the manufacture of artificial thread, a plurality of individual compartments, centrifugal spinning buckets in said compartments, air ducts connecting said compartments for maintaining the circulation of the air in said compartments, and refrigerating means surrounding each compartment for regulating the relative humidity therein.

parts for maintaining the circulation of the air in said compartments, and refrigerating means surrounding each compartment for regulating the relative humidity therein.

5. The method of preventing the formation of crystals in a spinning bucket compartment which comprises lowering the temperature of said compartment to increase the relative humidity therein.

6. The method of preventing the formation of crystals in a series of spinning bucket compartments which comprises lowering the temperature in said compartments to increase the relative humidity therein, circulating the air in said individual compartments, and circulating the air 15 through said series of compartments.

7. The method of preventing the formation of crystals in a spinning bucket compartment which comprises lowering the temperature to produce a relative humidity of at least 75%.

20 8. The method of preventing the formation of crystals in a spinning bucket compartment which comprises passing a refrigerating medium in proximity to said compartment to increase the relative humidity in said compartment.

25 9. The method of preventing the formation of crystals in a spinning bucket compartment which comprises passing a refrigerating medium in proximity to said compartment to lower the temperature thereof sufficiently to produce a relative humidity of at least 75% in said compartment.

PAUL E. HARRISON.
